UNITED STATES PATENT OFFICE.

OTTO F. FOGELSTRAND, OF KENSINGTON, CONNECTICUT, ASSIGNOR TO
HART MANUFACTURING COMPANY, OF SAME PLACE.

DESIGN FOR CUPBOARD-CATCH.

Specification forming part of Design No. 5,698, dated March 19, 1872.

To all whom it may concern:

Be it known that I, OTTO F. FOGELSTRAND, of Kensington, in the county of Hartford and State of Connecticut, have invented and produced a new and original Design for a Flush Cupboard-Catch, of which the following is a specification:

The nature of my design is fully represented by the accompanying engraving, to which reference is made.

A represents the body of the catch-case, and B the catch. The faces of these parts are bordered by a plain raised ledge, inside of which

are the screw-holes *a a a*. On the part A is a raised scroll-work figure, which extends between the screw-holes *a a*, and upon each side of the knob C. The sunken surface unoccupied by the raised figures and border is covered by fine check-work.

I claim as my invention—

The design for a flush cupboard-catch, as shown.

OTTO F. FOGELSTRAND.
